UNITED STATES PATENT OFFICE.

WILLIAM HAY, OF ARLINGTON, WASHINGTON, ASSIGNOR OF ONE-HALF TO NEIL BROWN, OF ARLINGTON, WASHINGTON.

CAR-SEAL.

1,256,896.

Specification of Letters Patent. Patented Feb. 19, 1918.

Application filed June 30, 1917. Serial No. 177,966.

To all whom it may concern:

Be it known that I, WILLIAM HAY, a citizen of the United States, residing at Arlington, in the county of Snohomish and State 5 of Washington, have invented certain new and useful Improvements in Car-Seals, of which the following is a specification.

This invention relates to car seals of the class conventionally known as "self-locking."

10 The object of my invention is to provide a car-seal of this character which will be an improvement over those hitherto in use.

With this end in view, the invention consists in the novel construction, adaptation 15 and combination of parts, as will be herein-after described and claimed.

In the accompanying drawings, Figure 1 is a view partly in side elevation and partly in longitudinal section through 1—1 of Fig. 20 3 of a car-seal embodying the present invention and showing the shackle member in locked engagement. Fig. 2 is a fragmentary longitudinal section of the same showing the shackle being introduced into the keeper or 25 casing member of the device. Fig. 3 is a plan view of Fig. 1. Fig. 4 is a plan view of the blank from which the casing and shackle are formed. Fig. 5 is a perspective view of the shackle-engaging device shown 30 detached.

Referring to the drawings, the numeral 6 represents a shackle member in the form of a narrow strip which extends from the lower element 7 of a shell or keeper member 8, 35 said shackle member being provided near its outer end with a rectangular slot 9.

The two aforesaid members are made of a single piece of sheet metal substantially of the form represented in Fig. 4, the wing elements 40 10¹ thereof being folded upwardly and inwardly to overlie each other, and are themselves overlaid at one end by a flap 11 and are reliably secured together as by soldering, brazing or in any other suitable manner.

Provided within said keeper is a locking device engageable with the free end of the shackle. Said device comprises a spring formed of a resilient plate bent at 12 to afford two arms 13 and 14, the former being rigidly secured to the keeper element 7 as by a rivet 15 and an offset lip 16 provided on the arm 13 extending through a hole in said element to engage against the bottom of the

latter. The other arm 14 is formed at each side with a shoulder 17 and thence extends as a tongue 18 of a width somewhat less than the width of the shackle slot 9 and has its extremity turned, as by a loop 18¹, about an element 19¹ of a link 19 to hingedly connect the same to the tongue 18. The length of this link is such that it will normally occupy the inclined positions in which it is represented in Figs. 1 and 2.

The tongue 18 is furthermore formed or 45 provided at a short distance from its extremity, with a downwardly directed protrusion 20 which serves as a stop against the slot edge 9¹ when the shackle is in the locked position in which it is shown in Fig. 1. 70

To employ the seal, the shackle is looped and its free end introduced into the entrance orifice 21 of the keeper and between the top thereof and the spring arm 14 (see Fig. 2) and then pushed rearwardly until the shackle orifice is in position to permit the tongue 18 of the referred-to arm to be thrust through the slot by the resiliency of the spring. The shackle end is then retracted by the operator while being deflected downwardly by the slot edge 9¹ encountering the curved surface of the tongue loop 18, and in its continued forward movement said slot edge engages and swerves the link 19 upwardly to permit the passage of the portion 6¹ of the shackle, 85 whereupon the link drops into its normal position and serves to guide the end of the shackle upwardly when the latter is moved for a short distance and cause the shackle portion 6¹ to be brought between the upper 90 end of the link and the protrusion 20 of the spring tongue 14, as clearly shown in Fig. 1.

With the parts in the positions just described, it is seen that the shackle end is prevented from being withdrawn from the keeper by reason of the spring tongue 18 extending through the shackle slot and the spring shoulders 17 bearing upwardly against the shackle to retain the shackle portion 6¹ in its lodged position between said link and the stop or protrusion 20. It is impossible to disengage the shackle because of the link, without destroying the keeper or at least mutilating it in a manner to indicate it has been tampered with. 100

What I claim, is—

A car seal comprising a keeper having a closed end, a shackle member integral there-

with and extending from the open end of the keeper, said shackle being provided with a slot adjacent to its outer end, a spring device within the keeper and comprising a plate bent to provide two arms, one of said arms being rigidly secured to the keeper, the other arm being formed with a tongue extending from two shoulders provided on the arm, and a link hingedly connected to the

outer end of said tongue and arranged to engage against the arm which is secured to the keeper. 10

Signed at Arlington, Washington, this 22nd day of June, 1917.

WILLIAM HAY.
